New York, Sept. 7, 1868.
Julia H. Herrick.

JULIUS HERRIET, OF NEW YORK, N. Y., ASSIGNOR TO DAVID WOLFE BRUCE, OF NEW YORK CITY.

Design No. 3,244, dated November 17, 1868.

DESIGN FOR ORNAMENTAL TYPE FOR PRINTERS.

The Schedule referred to in these Letters Patent and making part of the same.

To all whom it may concern:

Be it known that I, JULIUS HERRIET, of the city of New York, county of New York, and State of New York, have originated and designed a new pattern for printing-types, which I call Black Rim Shaded Capitals, reference being had to annexed printed impressions thereof.

It differs from every other kind of type in style, shape, and proportion.

What I claim as my invention, and desire to secure by Letters Patent, is—

The design or pattern for printing-types herein set forth.

JULIUS HERRIET.
